Primary Examiner — Prabhakar Deshmukh(74) *Attorney, Agent, or Firm* — Banner & Witcoff, Ltd.(57) **CLAIM**

The ornamental design for a directional pad for a controller, as shown and described.

DESCRIPTION

FIG. 1 is a front perspective view of a directional pad for a controller showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken line showing of the various unshaded elements of the directional pad for a controller in FIGS. 1–7 is for environmental purposes only and forms no part of the claimed design.
